Circular Banker of Clerks, New York
Letters Patent.

The subscriber referred to in the following patent and now having first
of this cause to commence an action upon the said Letters Patent
hereof to the sum of \$1000 and sue as a plaintiff for a deficiency and
for party damages.

To all whom it may concern.

I, Elmer C. St. John, Banker of Clerks in the County
of Orange and State of New York, have invented and improve
d a machine for cleaning and drying feathers. And I
do hereby declare that the following is a full and exact descrip
tion thereof. The machine may receive various dimensions
according to the quantity of feathers which are to be
acted upon at one operation. The measurements therefore
which I may indicate are only to be considered as relative
and belonging to one of ordinary size. I make a box or
receptacle for the feathers of that size. This box may be
filled by the feathers wide and three feet deep. Its lower
half immediately, or in any other place horizontally divided so that
that the feathers may not triflely. A reel or revolving basket is
placed within this box. The rods of both are firmly placed
upon, it shall come mainly in contact with the cylindrical basket
and the rest of the feathers, one of the ends of the shaft pass-
ing through the end of the box to communicate the requisite
motion to it. The cover of the box may consist of a cloth stretched
upon a suitable frame. The bottom of it is to be punctured with
numerous holes to admit of the passing of heat air into it
and to allow of the escape of the dust. . . . Separated from the
feathers in the process of drying ^{towards the} immediately before them
is a place for the feathers. I place stone slates which may be fast with
strong suitable springs at each end of the machine. These
slates or slates are to be arranged as to collect the heat air
equally on from the under surface of the box and to collect

it is bound on two firm four inch square pillars of iron, and must be
 upon the upper side of the floor, near the bottom of the box;
 A depth of about a foot may be allowed for the lower part,
 A frame or railing made of wood is made to run in the four
 posts, and the instance of the box I have with
 me is made with this plate the wood being a bad
 conductor of heat will prevent its combustion, and the absence
 of such will render the fire well above the apparatus sufficient
 light to render it altogether practicable, and reasonably ready
 for use. For the purpose of this purifying the feathers, I divide
 the wooden box into two parts, at or near its middle, hori-
 zontally, and range these parts together on one side, by which
 arrangement the feathers when deposited, can all be washed out
 by turning the upper part over. These feathers are to be deposited
 upon them into the box named receptacle and pour upon
 it over the small quantity of water and when the fire has been
 lighted in the stove keep the feathers in constant motion by lurn-
 ing the wooden box or table, as the water evaporates the feathers
 will become perfectly dry and the dust will be separated from
 them, & as to render them clean, a precious washing being rarely
 if ever found necessary.

What I claim as my invention is the construction of a ma-
 chine for drying and cleaning feathers, furnished with a box or
 receptacle such as I have described and in which they are dis-
 posed up or agitated by the revolution of said receptacle in the man-
 ner set forth. I also claim the covering of the stove or furnace with
 a wooden box lined with metal, and the holes for the admission
 of heated air, and the discharge of dust through the bottom
 of the receptacle. I also claim the construction of the
 wooden box or frame in such a manner that the whole of the dust
 feathers may be discharged therefrom at once.
